UNITED STATES PATENT OFFICE

HENRY LEE BASSETT, OF COLUMBUS, INDIANA, ASSIGNOR TO COLUMBUS HANDLE & TOOL CORPORATION, OF COLUMBUS, INDIANA, A CORPORATION OF INDIANA

SHOVEL HANDLE

Application filed July 15, 1929. Serial No. 378,347.

My invention relates to tool handles, particularly to shovel handles, and more particularly to the construction of a sheet metal D-head for such handles. The object of the 5 invention is to provide such a D-head which will embody all the desirable features required in the use of such handles, and one which will provide a handle with a head of comparatively great strength as well as one 10 that can be produced at comparatively low cost; all as will be hereinafter more fully described and claimed.

In carrying out my invention I employ two sheet metal stampings, one of which is of D 15 formation and provides the diverging tubular arms of the head, and the other of which is adapted to fit around the intermediate portion of the other member as a yoke or saddle for securing the head to the stile.

20 Referring to the accompanying drawings, which are made a part hereof and on which similar reference characters indicate similar parts,

Figure 1 is a front elevation of a handle 25 head of the construction which constitutes my invention,

Figure 2, a similar view with part of the head shown in vertical section to better illustrate the construction,

30 Figure 3, a section on the line 3—3 of Fig. 1,

Fig. 4, a plan view of the blank from which the stile socket saddle is formed, and

Figure 5 is a perspective of the saddle 35 shown in Fig. 4 after it has been stamped into shape ready for application to the D-member.

Figure 6 is a modified form in which the D-portion is made from two pieces.

40 In the drawings reference character 10 indicates the primary sheet metal stamping which forms the D-member and 11 the secondary sheet metal stamping which forms the saddle or yoke which fits around and reinforces the primary member 10, and at the same time affords means for attaching the D-member to a stile 12.

The primary sheet metal stamping is of the same general shape as the corresponding 50 portion of the ordinary wood or sheet metal

shovel handle and is provided with tubular arms 13 curved outwardly from a central depression α , formed to receive the top of the stile 12 and which extend upward and terminate in the usual opposed sockets 14', at their 55 upper ends for reception of the ends of a handle-grip 15. The handle-grip is preferably of wood and is held in place by a bolt or rivet 16 which passes longitudinally through the same below or above the center 60 or eccentrically in order to prevent turning of the grip in the grip sockets.

The head part with the tubular arms 13 is integrally formed and said arms taper gradually in both width and thickness 65 throughout their length, the smallest portion of the arms being adjacent their upper ends or where they join the sockets for the grip 15. The edges of the metal forming the arms are brought together along the central portion 70 of the inside of the arms. The intermediate portion of the head member is reduced in size, the depression corresponding to the thickness of the metal forming the yoke or saddle 11, which forms the stile socket. By this 75 means a seat for the saddle is formed, and the completed handle is formed with a smooth surface. The seat α for the reception of the end of the stile 12 is formed by a depression in the under side of the D-head, or in the side remote from the grip 15.

80 The saddle or yoke 11 which secures the D-member to the stile is formed from an elongated blank of the form shown in Fig. 4 and is stamped or pressed to form its central portion 14 transversely curved to conform to the curvature of the inner surface of the D-member, upon which it snugly fits, and the side portions 18 adjoining the central portion 14 are likewise formed longitudinally 85 curved to conform to the sides and under surface of the D-head. The extremities of the blank are curved transversely to form semi-cylindrical sections 19 of identical size which are adapted to form the stile socket. The head is fastened to the stile by rivets 20, which pass through the socket and stile and 90 secure the parts rigidly together. The handle just described has a substantially smooth surface and is of comparatively great 95 100

strength, while of simple and inexpensive construction.

In Figure 6 is shown a modified form of the D-portion. In this construction the arms of the D-portion are made from two separate blanks which are formed to shape the halves of the handle and are then welded together at 21. In other respects the head is similar to the construction shown in my application No. 360,259, filed May 3, 1929, and this application is therefore filed as a continuation in part of said application.

It will be obvious to those skilled in the art that various changes may be made in my device without departing from the spirit of the invention, and I therefore do not limit myself to what is shown in the drawings and described in the specification but only as set forth in the appended claims.

Having thus fully described my said invention, what I claim as new and desire to secure by Letters Patent, is:

1. A sheet metal D-head for handles comprising a main part of sheet metal stamped to form a pair of tubular arms provided at their extremities with opposed grip receiving sockets and a central depression, and a saddle formed of a separate piece to fit in the depression about the central portion of the head and provide a stale socket, substantially as set forth.

2. A sheet metal head for handles comprising a D-member pressed from a single piece of sheet metal and having a pair of tubular arms with opposed grip sockets at their outer ends, said D-member having its intermediate portion reduced to form a seat for an attaching member, and a saddle member for securing said head to the stale, substantially as set forth.

3. A sheet metal head for handles comprising a D-member pressed from a single piece of sheet metal and having a pair of tubular arms with opposed grip sockets at their outer ends, said D-member having its intermediate portion reduced to form a seat for an attaching member and a depression for a seat for the end of a stale, and an attaching member for securing the D-member to the stale comprising a body bent to fit around said D-member and to form half sections of a stale socket, substantially as set forth.

4. A sheet metal D-head for handles formed in two parts, one part being formed with a central depression in which the end of the stale may seat and having arms diverging from said central portion and curved outwardly and extending upwardly and having grip receiving sockets in their opposed upper faces, and the other part consisting of a saddle or stirrup adapted to embrace the central portion of the first named part and extend down on opposite sides of the stale and be secured thereto, whereby said two

parts are secured together and the head as a whole is secured to the stale, substantially as set forth.

5. A sheet metal head for handles comprising two parts, the main part or head being formed D-shaped and hollow and adapted to carry the grip at its upper end, and the other part formed to embrace the central portion of the D part and extend down on opposite sides of the stale, said two parts being formed with interengaging shoulders which connect at the central portion to embrace the stale, whereby the parts may be secured together and the head to the stale by securing devices, substantially as set forth.

6. A sheet metal head for handles comprising a main part formed D-shaped and hollow and adapted to support a grip at its upper end, and with a central depression in its under side to receive the end of the stale, and another part formed to embrace the central portion of the D-part and extend down on opposite sides of a stale and embrace the stale, whereby the parts may be secured together and the head to the stale by securing devices, substantially as set forth.

In witness whereof, I have hereunto set my hand at Columbus, Indiana, this 11th day of July, A. D. nineteen hundred and twenty-nine.

HENRY LEE BASSETT.
